TIMING DEVICE

Joseph F. Merkel, Rochester, N. Y., assignor to
General Railway Signal Company, Rochester,
N. Y.

Application August 6, 1947, Serial No. 766,615

5 Claims. (Cl. 175—320)

1

This invention relates to timing devices and it more particularly pertains to improvements in timing devices actuated by a constant speed motor.

There are certain applications, particularly in railway signaling, where a time interval of substantial duration must be accurately and dependably measured. For example, it may be desired to impose a restricted signal penalty on a train unless the train consumes a certain amount of time within a particular predetermined distance. The timing in this case is indicative of the maximum speed the train may travel without penalty, and a high degree of accuracy in timing is required. It is also required that the timing device after having been used to time the passage of one train must be quickly restored to condition it for timing the next train, thus preventing a following train from gaining advantage of timing which has been effected by a train in advance.

An object of the present invention is to provide an improved, economical, rugged, and dependable timing device to meet the above requirements.

Another object of the present invention is to render the timing device responsive to alternating current input, such input being effective to energize a synchronous motor which is effective to drive a mechanical timing mechanism through a direct current magnetic clutch energized from the alternating current input through a suitable rectifier unit.

An object in the use of the magnetic clutch is to allow the mechanical timing mechanism to be restored by gravity upon removal of input energy to the timing device, without having to drive the synchronous motor backwards through reduction gearing and without requiring the disengagement of any gears.

Another object in the use of a magnetic clutch is to improve the accuracy of the timing device upon initiation as compared to the accuracy of timing devices in which the engagement of gearing at the initiation of the devices may gain or lose time dependent upon the relative positions of the gears when they are brought into mesh. The magnetic clutch also has the advantage of being less susceptible to wear than small gearing that must be intermittently engaged and disengaged.

Another object of the present invention is to provide a primary-secondary timing device organization wherein the direct current magnetic clutch and a secondary relay are operated from

2

the alternating current input to the device through a step down transformer and rectifier; wherein the secondary relay is energized in response to closing of contacts of the timing mechanism; wherein the secondary relay in response to its energization de-energizes the motor and the magnetic clutch; and wherein the direct current secondary relay is maintained energized by a stick circuit dependent upon input alternating current to the timing device.

Other objects, purposes and characteristic features of the present invention will be in part obvious from the accompanying drawings and in part pointed out as the description progresses.

15 In describing the invention in detail, reference is made to the accompanying drawings in which similar reference characters are used to designate corresponding and similar parts in the respective views; and in which:

20 Fig. 1 is an elevational view shown partly in cross section of the principal operating parts of the timing device of an embodiment of the present invention;

Fig. 2 is an end elevational view of a portion 25 of the timing device showing particularly the mechanically actuated timing contacts; and,

Fig. 3 shows in perspective the principal operating elements of the timing device according to the present invention with certain parts being 30 shown in cross section or in expanded relationship for the purpose of facilitating the disclosure. Fig. 3 also shows schematically the circuit organization for the control or respective elements of the timing device.

35 With reference to Fig. 3, a conventional synchronous motor SM is provided with a suitable reduction gearing RG the output of which is applied to the pinion 10 which drives through a suitable gear 11 the drive shaft 12 extending 40 through the center of the magnetic clutch MC.

The magnetic clutch case C (see Fig. 1) is of magnetic material such as silicon steel, and it provides a housing for the winding 13 of the magnet as well as forming a part of the magnetic circuit. The end plate 14 of the case C has a center opening within which is threaded the core 15 which is formed of suitable soft iron material such as silicon steel. The core 15 is concentric with the shaft 12 and thus has an 45 opening extending longitudinally through its center for passage of the shaft 12. The assembly of the winding within the case C is accomplished by the insertion of the winding over the core and against a suitable washer 16 whereby the 50 pole piece 17 at the left-hand end of the core

15 draws the winding 13 tightly within the casting C when the core 15 is threaded into the end plate 14 of the case C.

With reference to Fig. 1, suitable bearing inserts 18 and 19 at the respective left- and right hand ends of the core 15 are provided for journaling the drive shaft 12 which is preferably of non-magnetic material. The short portion 20 of the shaft 12 extending immediately to the left of the bearing 18 is squared, or otherwise formed to accommodate the drive disc 21 so as to cause that disc to be rotated by the drive shaft 12. The drive disc 21 is preferably of non-magnetic material and is formed as shown in Fig. 1 with its center area having a reduced cross section to allow space for the dished spring 22 which is assembled on the drive shaft 12 at the left of the drive disc 21 to bias the clutch MC to a disengaged position.

The driven mechanism of the clutch MC is rotated by the motor SM only when the clutch MC is energized, and its parts are free to slide longitudinally and rotate about the driven shaft 12.

The driven disc 23 is suitably secured as by riveting at the point 24 to a squared portion of the hub 25 which is slidably fitted on the left-hand end of the drive shaft 12, such hub being formed with longitudinally spaced bearing ends for rigidly supporting the driven disc 23 concentric with the drive shaft 12. The hub 25 when assembled on the left hand end of the drive shaft 12 is spaced by the washer 26 from the dished spring 22.

The driven disc 23 has a reduced cross section area near its center as it is only desired to use the outer surface 27 as a clutch face. The disc 23 has secured therein the contact pins 28 which extend slightly beyond the right-hand surface 29 of the driven disc 23, and it is thus these contact pins 28, because of their friction against the drive plate 21, that provides the operable connection between the drive and the driven discs 21 and 23 respectively. It has been found that three of these pins 28 are sufficient when they are spaced substantially 120° apart about the surface 29 of the driven disc 23.

The pinion gear 30 is slidably fitted over the hub 25, and the right-hand end of the gear 30 is squared so as to be rotatably secured to the washer 31. The washer 31 is biased against the driven disc 23, through the pinion gear 30, by the coil spring 32 at the left-hand end of the pinion gear 30. The spring 32 is assembled over the hub 25, and is maintained under tension by the washer 33 which is also assembled on the left-hand end of the hub 25 and is held in position by the key 34 that is fitted into a suitable slot near the left-hand end of the hub 25. The lock nuts 35 are threaded onto the end of the drive shaft 12 against the left-hand end of the hub 25 to maintain the spring 22 under compression, and to maintain the desired normal clearance between the pins 28 of the driven disc 23 and the contact surface 36 of the drive disc 21.

By this structure of the driven mechanism of the clutch MC, it is provided that the driven disc 23 and pinion 30 organization is free to rotate about the drive shaft 12 when the magnet is deenergized, and the structure further provides that the gear 30 can be rotated with respect to the driven disc 23 by slippage between the washer 31 and the contact surface 27 of the

driven disc 23 for purposes to be hereinafter considered.

The gear 30 drives a vertically disposed toothed rack 37 of a time contactor mechanism. The rack 37 is substantially square in cross section and it is maintained in lateral alignment with its teeth engaged in mesh with the pinion gear 30 by the roller 38 which is engaged in a longitudinal slot 39 on the opposite side of the rack 37 from the teeth 40. The roller 38 is suitably secured as by the pin 41 within a bracket 42 which is held in alignment and secured to the fixed supporting bracket 43 by the pin 44 and the screw 45.

Secured to the lower end of the rack 37 is a double break contact member comprising a plate 46 of good conducting material extending across the lower end of the rack 37. At each end of the plate 46 front contact points 47 are secured to its upper surface and back contact points 48 are secured to its lower surface. The front contact points 47 which are secured to the upper surface of the contact plate 46 are preferably of silver impregnated carbon which are suitably secured to the contact plate 46 as by the contact sleeves 49 of copper or other low resistant material. The contact sleeves 49 have ears 50 extending through the contact plate 46 and suitably secured thereto as by solder. The back contact points 48 are secured as by solder to the lower side of the plate 46 and they are of low resistant material such as silver or tungsten, although it is to be understood that contact points of other materials could as well be used if required in practice.

The contact plate 46 is secured to the lower end of the rack 37, so as to be insulated from the rack 37, by the screw 51 which extends through upper and lower insulation blocks 52 and 53 and through the insulating sleeve 54 which insulates the threads of the screw 51 when passing through the contact plate 46. The upper block 52 of insulating material maintains the contact strip in alignment with the rack 37 by the detents 55 and 56 which engage in recesses in the rack 37 and contact plate 46 respectively. The screw 51 is locked in its tightened position by the transverse pin 57. The contact plate 46 is notched at the point 58 as more clearly illustrated in Fig. 3 to allow clearance for the supporting rod 59.

The contact fingers 60 and 61 of the adjustable member AC are spaced on opposite sides of the rack 37 and so disposed so as to cooperate with the double break contact points 47 so as to close a circuit between the fingers 60 and 61 when actuation of the timing device is complete.

The contact fingers 60 and 61, together with their respective supporting fingers 62 and 63, are suitably secured to the transverse plate 64 of insulating material as by the screws 65 which extend through longitudinal 90° metal brackets 66 on the opposite sides of the rack 37, such screws being insulated by suitable bushings (not shown) and by insulation plates 67 from such brackets 66. Disposed between the brackets 66 are two pairs of rollers 68 and 69 bearing against the respective front and back sides of the rack 37. The rollers 68 and 69 are pivoted by the pins 70 which extend between the brackets 66, and they are provided with suitable spacers 71 for maintaining the rollers close to the edges of the respective sides of the rack 37 with which they are associated. Thus on the toothed side of the

rack 37 one roller 68 rides against the rack 37 on each side of the teeth 40.

The adjustable contact carrying member AC is adjustable in that its elevational position is determined by the threaded rod 72 which is threaded through the hub 73, the hub 73 being suitably secured within the plate 64 of insulating material. It is thus provided that the turning of the threaded rod 72 as by the screw 74 through the bevel gears 75 and 76 is effective to drive the adjustable contact carrying member AC up and down the rack 37 and thus vary the distance the rack 37 must travel before the double break contact points 47 at the lower end of the rack 37 close a circuit from contact finger 60 to contact finger 61. The lower end of the threaded rod 72 is journaled in the fixed plate 77 at the base of the relay at the point 78 (see Fig. 2), and end play in the threaded rod 72 is taken up by the spring 79 acting against the washer 80 and the shoulder 81 of the threaded rod 72.

By the use of a fixed rod 59 extending from the point 82 (see Fig. 2) in the supporting bracket 43 to the point 83 in the base plate 77, extending through the slot 84 in the outer edge of the plate 85, the adjustable contact carrying member AC is maintained in alignment between two fixed points. With the rack 37 extending through the adjustable contact carrying member AC between the guide rollers 68 and 69 at the front and back of the rack 37, and between the brackets 66 at the sides of the rack 37, the adjustable contact carrying member AC serves as a lower bearing for the rack 37 to insure the contacts 60 and 61 to be in accurate alignment at point of contact with the double break front contact points 47.

Cooperating with the double break back contact points 48 at the lower side of the contact strip 46 are contact fingers 86 and 87 disposed on opposite sides of the rack 37. These contact fingers 86 and 87 together with supporting fingers 88 are suitably secured as by the rivets 89 to the block 90 of insulating material, which block 90 is suitably secured to the base plate 77 as by the rivets 91 as shown in Fig. 2. It is thus provided that an electrical connection is closed between the lower contact fingers 86 and 87 only when the rack 37 is restored to its dropped away position as is illustrated in the accompanying drawings. The adjustment screw 92 and lock nut 93 in the base plate 77 serves to provide a stop for limiting the downward movement of the rack 37, rather than having the back contact fingers 86 and 87 absorb the entire shock when the rack 37 is released by the magnetic clutch MC.

Aside from the parts of the timing device that have been described, with reference to Fig. 3, the device includes a direct current secondary relay SR, a rectifier unit R, and a step down and insulating transformer T. The terminals 94 and 95 are the input terminals to the timing device, and the switch SW is to be understood as merely symbolic of any switch or any contact of any device which may be employed in practice to render the operation of the timing device effective.

Having thus considered the general organization and structure of the timing device according to the embodiment illustrated, consideration will now be given as to the mode of operation of the device under certain typical assumed operating conditions. To consider operation of the device, it will be assumed that the switch SW is closed to apply alternating current from a suitable source

such as a 110 volt A. C. supply, the symbols BX and CX being used to designate the respective instantaneous positive and negative terminals of such source of supply.

It is thus provided that the closing of the switch SW for effecting operation of the timing device applies alternating current directly to the input terminals 94 and 95 of the device. The application of energy to the input terminals 94 and 95 of the timing device energizes the primary winding 96 of the transformer T directly and also applies alternating current to the synchronous motor SM through the back contact 97 of the secondary relay SR. The input terminals of the rectifier unit R are directly connected to the secondary winding 98 of the transformer T, and thus direct current is available at the output terminals of the rectifier R whenever alternating current energy is applied to the input terminals 94 and 95 of the timing device.

With direct current energy applied at the output terminals of the rectifier R, the winding 13 of the magnetic clutch becomes energized by a circuit extending from the positive terminal of the rectifier R including back contact 99 of relay SR, and winding 13 of the magnetic clutch MC, to the negative terminal of the rectifier R. The energization of the magnetic clutch MC sets up a magnetic field (see Fig. 1) in a magnetic circuit extending from the pole piece 17, through the disc 23, the case C and the core 15. It is preferable that the disc 21 be of non-magnetic material such, for example, as Phosphor bronze so that the sensitivity of the clutch is improved by the disc 23 providing the only path of low reluctance between the core 15 and the case C, the disc 23, the core 15 and the case C all being of magnetic material such as silicon steel having relatively low reluctance. The setting up of the magnetic circuit as described thus acts upon the disc 23 to attract the disc against the bias of the spring 22, to cause the contact pins 28 to contact the surface 36 of the disc 21 and thereby cause rotation of the driven disc 23 to be effective in accordance with the rotation of the drive disc 21. The attraction of the disc 23 is such as to urge the pins 28 tightly against the disc 21 so as to prevent slippage and cause the rotation of the driven disc 23, and thus the driving of the pinion gear 30, to be in correspondence with the rotation of the drive disc 21.

The direction of the drive of the gear 30 is counterclockwise as viewed in Fig. 2, and is necessarily at a constant rate of speed determined by the speed of the synchronous motor SM and its associated reduction gearing RG. The initial raising of the rack 37 is effective to open the double break contact connection between the back contact fingers 86 and 87, and thus open a check circuit which is usually employed in connection with the use of timing devices of this character to check that full restoration of the device is effected after each operation.

The time consumed in the raising of the rack 37 before a circuit is closed between the contact fingers 60 and 61 of the adjustable contact member is dependent upon the adjusted elevational position of the adjustable contact member as is conveniently indicated by a suitable scale 100 (see Fig. 2) which is secured as by the rivet 101 to the rod 59. This scale is preferably graduated in seconds so disposed as to read opposite the contact fingers 60 and 61 the number of seconds consumed in the raising of the rack 37 to the

point where the contact points 47 close a circuit between contact fingers 60 and 61.

The closing of a circuit between contact fingers 60 and 61 is effective to energize the secondary relay SR with direct current by a circuit extending from the positive terminal of the rectifier R and including contact finger 61, contact finger 60, and winding of relay SR to the negative terminal of the rectifier R. The secondary relay SR preferably has its contact 99 adjusted as a make-before-break contact as illustrated in order that the shifting of contact 99 upon the energization of relay SR may close a stick circuit at front contact 99 prior to the opening of the pick up energizing circuit that has just been described. It is thus provided that the picking up of the relay SR is effective by the closure of its front contact 99 to shunt the contact fingers 60 and 61 out of its energizing circuit and thus maintain the secondary relay SR in its energized condition so long as alternating current is applied to the input terminals 94 and 95 of the timing device.

The closure of front contact 102 of secondary relay SR is effective to govern any time control circuit in accordance with the requirements of practice, such, for example, as a circuit permitting the clearing of a signal for a train. It can thus be provided that the alternating current energy can be applied to the input terminals 94 and 95 of the timing device by a train entering a particular section, and by delaying the closure of front contact 102 of the secondary relay SR for a particular length of time, it can be required that the train take a particular predetermined amount of time in that section in approaching a signal before such signal is allowed to clear by the closure of front contact 102.

Upon the picking up of the secondary relay SR in response to the closure of a circuit between the contact fingers 60 and 61 of the timing device, the alternating current energy is removed from the synchronous motor SM by the opening of back contact 97, and the opening of back contact 99 deenergizes the magnetic clutch MC. Upon deenergization of the magnetic clutch MC, the disc 23 (see Fig. 1) is restored to its left-hand position by the spring 22 so as to be disengaged from the drive disc 21, and immediately upon such restoration, the disc 23 and the gear 30 are allowed to turn free on the drive shaft 12. They are driven in a clockwise direction by the weight of the rack 37 until the rack 37 reaches its fully dropped away position. When the rack 37 reaches its fully dropped away position, the contact of the screw 51 with the stop 92 (see Fig. 2) brings the dropping away of the rack 37 to a stop, and for purposes of preventing possible damage to the small teeth of the gear 30 and of the rack 37, the washer 31 slips with respect to the driven disc 23 to prevent damage to the teeth in an abrupt stop because of the inertia of the relatively heavy disc 23. When the rack 37 is fully dropped away as has been described, a connection is again made between the check contact fingers 86 and 87, but, with the relay SR still up, the check circuit is held open at back contact 103. When the control circuit for the timing device is opened as by the opening of the switch SW, energy is removed from the rectifier R, and thus the secondary relay SR is dropped away so as to open its stick circuit at front contact 99 and close back contact 99 to complete the conditioning of the timing device for a subsequent mode of operation upon again closing the switch SW.

From the structure and mode of operation of the timing device as it has been described, it will be apparent that the timing device has the advantage of accuracy due to use of a synchronous driven motor; the problems of engagement and disengagement of the driving mechanism for the rack 37 is solved in a manner by use of the magnetic clutch MC whereby no time is lost or gained upon initiation of the device as is inherent by timing devices where the meshing of gears is required upon initiation of the device; the use of double break contact organizations accomplishes the control of circuits without requiring wiring connections to the movable contact points associated with the rack 37; the magnetic clutch MC and the secondary relay SR operate at their greatest efficiency because of being operated on direct current but yet require no source of direct current outside of the timing device; and the dropping away of the rack 37 upon the picking up of the secondary relay SR is effected without shock to the small teeth of the rack and pinion because of inertia of parts of the magnetic clutch MC.

Having thus described a specific timing device as one embodiment of the present invention, it is to be understood that this form of the invention has been selected principally to facilitate its disclosure and that various adaptations, alterations, and modifications may be applied to the specific form shown to meet the requirements of practice without in any manner departing from the spirit or scope of the present invention except as limited by the appending claims.

What I claim is:

1. In a timing device driven by a constant speed motor, a contactor mechanism comprising, an elevationally disposed toothed rack driven by said motor, a double break contact member secured to the lower end of said rack, said contact member having two laterally spaced contact points, and said contact points being electrically connected together, and an elevationally adjustable contact carrying member having two laterally spaced contact fingers insulated from each other, said fingers being so disposed as to cooperate with said contact points respectively when said rack is raised by said constant speed motor and said adjustable contact carrying member having a portion journaling said rack substantially at the elevational position where the points of said double break contact member contact said contact fingers when said rack is raised by said motor, whereby the contact points are most accurately aligned with the contact fingers at the elevationally operated position of said rack where an electrical connection is closed from one of said contact fingers to the other by the double break contact member.

2. In a timing device driven by a constant speed motor, a magnetic clutch having a drive disk rotated by said motor through reduction gearing and a driven disk of magnetic material normally biased away from said drive disk but attracted to it by the energization of the winding of said clutch, a friction disk, a pinion gear driven by said driven disk through said friction disk, an elevationally disposed tooth rack engaging said pinion gear and operable between upper and lower limit positions, front and back contact points secured to the lower end of said rack, an elevationally adjustable contact finger closed with said front point upon the raising of said rack, a fixed contact finger closed with said back con-

tact point only when said rack is in said lower limit position, and electro-responsive means responsive to the closure of said elevationally adjustable contact finger with said front point for deenergizing said magnetic clutch and permitting the restoration of said rack by gravity to its lower limit position, irrespective of said constant speed motor and said reduction gearing, whereby said rack is quickly restored by gravity to its lower limit position once operation of the timer has been completed to close a front contact, and whereby slippage between said friction disk and said driven disk when the rack reaches its lower limit position prevents the inertia of said driven disk from damaging the teeth of the rack.

3. A timer having input terminals to which alternating current is selectively applied for operation of the timer comprising, an alternating current constant speed motor, an elevationally disposed toothed rack having contact points secured thereto, a magnetic clutch coupling said motor with said rack only when said magnetic clutch is energized, a secondary relay, circuit means including said contact points for energizing said secondary relay when said rack is elevated by said motor to a predetermined elevationally adjustable position, stick circuit means for maintaining said secondary relay energized in accordance with the application of alternating current to said input terminals, clutch energization means including a rectifier for energizing said magnetic clutch from the alternating current applied to said input terminals, said clutch energization means being effective only when said secondary relay is deenergized, and means for rendering said motor active in response to alternating current applied to said input terminals only provided that said secondary relay is deenergized.

4. A timer having two input terminals to which alternating current is selectively applied for operation of the timer comprising, an alternating current constant speed motor, an elevationally disposed tooth rack having contact points secured thereto, a magnetic clutch coupling said motor with said rack only when said magnetic clutch is energized, a secondary relay, circuit means including said contact points and a rectifier for

5 energizing said secondary relay from energy applied to said input terminals when said rack is elevated by said motor to a predetermined elevationally adjustable position, stick circuit means effective when said secondary relay is picked up to maintain that relay picked up dependent upon the alternating current applied to said input terminals, and clutch energization means for energizing said clutch in response to the application of alternating current to said input terminals, said means being effective only when said secondary relay is deenergized.

10 5. A timer of the character described having two input terminals to which alternating current is selectively applied comprising, an alternating current constant speed motor, an elevationally disposed tooth rack having contact points secured thereto, a magnetic clutch coupling said motor with said rack only when said magnetic clutch is energized, a secondary relay, a rectifier, 20 circuit means including said contact points and said rectifier for energizing said secondary relay from energy applied to said input terminals, said circuit means being rendered effective only when said rack is elevated by said motor to a predetermined elevationally adjustable position, stick circuit means including said rectifier for maintaining said secondary relay energized dependent upon alternating current energy applied to said input terminals, clutch energization means for energizing said clutch through said rectifier from said input terminals, said clutch energization means being effective only so long as said secondary relay is deenergized.
